UNITED STATES PATENT OFFICE.

LUCIUS D. COPELAND, OF CAMDEN, NEW JERSEY.

FLY-WHEEL.

SPECIFICATION forming part of Letters Patent No. 393,059, dated November 20, 1888.

Application filed November 19, 1887. Serial No. 255,632. (No model.)

To all whom it may concern:

Be it known that I, LUCIUS D. COPELAND, a citizen of the United States, residing at Camden, in the county of Camden and State of New Jersey, have invented certain new and useful Improvements in Fly-Wheels for Steam-Engines; and I do hereby declare the following to be a full, clear, and exact description of the invention, reference being had to the accompanying drawings, which form part of this specification.

This invention has relation to fly-wheels or main pulleys for steam-engines and other motors, and particularly to that class of wheels or pulleys in which a ratchet wheel and pawl or dog are employed to allow the wheel to turn in one direction independently of the shaft upon which it is mounted.

My invention consists in the combination, with the engine or motor shaft having a conical head or spindle and carrying a ratchet-wheel, of the fly-wheel or pulley having a conically-recessed hub and carrying a pawl which engages with said ratchet, with devices for holding the wheel upon the shaft and preventing binding of the same.

In the accompanying drawings, Figure 1 is side view of a fly-wheel or pulley upon the main shaft of an engine provided with my improved appliance; Fig. 2, a transverse sectional view on line $x-x$ of Fig. 1, and Fig. 3 a section of a detail. Fig. 4 is a central sectional view showing the conical hub and the wheel mounted thereon.

A designates the main shaft of an engine or motor, and B the fly-wheel or main pulley.

Instead of keying or otherwise rigidly securing the fly-wheel to the main shaft, I fit the former loosely upon the shaft, and in order to give it ample bearing-surface and prevent bending I provide the shaft with a tapering or conical head, a , and correspondingly taper the hub of the wheel. Upon the outer face of the hub I place a disk or washer, b , and secure the same in place by means of a screw or bolt, d , and a spiral spring, d' , the latter being

situated between the head of the bolt and the face of the washer. When freely rotating, the tendency of the wheel will be to move toward the end of the shaft and become loose upon its bearings. This is an advantage, and I employ the spring so that it may yield sufficiently under the pressure of the wheel to free the latter from close or binding contact with the conical bearing.

Upon the main shaft adjacent to the inner face of the wheel is fixed rigidly a ratchet-wheel, D, while pivoted to one of the spokes of the wheel is a pawl, d' , engaging with the teeth of the ratchet and held in close contact or engagement therewith by a spring, e , one end of which is inserted in the outer surface of the spoke, from which the spring is bent back upon itself and under the spoke. The main shaft is supposed to rotate in the direction of the arrow upon the face of the ratchet, and through said ratchet and pawl transmits motion to the fly-wheel. Now, in the event of the sudden stoppage of the engine and shaft, which may result from priming in the boiler, causing a sudden stoppage of the piston, the fly-wheel will continue notwithstanding to revolve, the pawl sliding over the beveled faces of the ratchet-teeth until the momentum is exhausted.

Having described my invention, what I claim is—

The combination, with the shaft A, having a conical head or spindle, a , and carrying a ratchet-wheel, D, of the fly-wheel or pulley B, having a conically-recessed hub and carrying the pawl d' , engaging with said ratchet, the disk or washer b , spring d' , and screw or bolt d , substantially as described.

In testimony that I claim the foregoing I have hereunto set my hand this 14th day of November, 1887.

LUCIUS D. COPELAND.
